UNITED STATES PATENT OFFICE.

JOSEPH S. BARUCH, OF NEW YORK, N. Y.

CARBURETER.

1,213,817.

Specification of Letters Patent. Patented Jan. 30, 1917.

Application filed October 29, 1913. Serial No. 797,983.

To all whom it may concern:

Be it known that I, JOSEPH S. BARUCH, a citizen of the United States, and a resident of New York city, in the county and State 5 of New York, have invented a new and useful Improvement in Carbureters, of which the following is a specification.

My invention relates to carbureters, and one of the objects of the invention is to provide a simple, durable and efficient carbureter.

Another object of the invention is to provide a carbureter having an internally heated chamber within the shell of the carbureter so arranged with respect to the adjacent walls of the shell or to other walls within which the mixture flows, as to form therewith a portion of the passageway for conducting hydrocarbon fuel mixture to the engine, the passageway being of such dimensions as to insure the proper heating of the mixture and vaporization of the hydrocarbon.

Another object of the invention is to produce a carbureter which may be cheaply constructed and which has few parts to be adjusted or tampered with by inexperienced operators.

Further objects of the invention will more 30 fully appear from the following description of the preferred embodiment of my invention taken in connection with the accompanying drawings illustrating the same, in which—

35 Figure 1 is a sectional elevation of the preferred embodiment of the carbureter; Fig. 2 is a horizontal sectional view of the same taken on line 2—2 of Fig. 1; Fig. 3 is a side view of a portion of the carbureter 40 looking in the direction of the arrow 3 (Fig. 1); Fig. 4 is a bottom view of the lower portion of the carbureter looking in the direction of the arrow 4 (Fig. 1); and Fig. 5 is a view of a portion of the carbureter looking 45 in the direction of arrow 5 (Fig. 1).

The main shell of the carbureter comprises a spherical portion 6 with upper and lower cylindrical extensions 7 and 8, each of less diameter than the spherical portion 50 6, the lower extension 8 being of considerably less diameter than the upper extension 7 and being provided with an air inlet opening 8'. The lower half of the cylindrical portion of the shell is preferably formed integrally with the lower extension 8, which in turn is connected through a horizontal

connecting piece 9 with a hydrocarbon tank 10, and the lower extension is also provided with a hydrocarbon nozzle 11 supported by suitable webs 12, and this nozzle and the horizontal connecting portion 9 are bored out to form a communicating passageway to the tank 10. The nozzle preferably extends into close proximity to the outer wall of a heating chamber 13 hereinafter referred to. 60 The upper half of the spherical portion of the shell 6 is preferably formed integrally with the upper extension, which in turn is provided with horizontal cylindrical flanges 14 and 15 bored out to form bearings for a 65 horizontal cylinder 16 having suitable ports 17 so as to serve as a rotary throttle valve. The flange 15 has a cap 18 threaded thereon through which extends a spindle 19, the inner end of which is secured to the hub 20 70 of the valve cylinder 16 to rotate the same when the spindle is operated by the crank 21. The cylindrical flange 14 at the opposite end of the cylinder has an end plate 14' 75 cut away to form ports 22 for admitting auxiliary air, and the size of these openings or ports is regulated by a vane 23 rotatably mounted on the central or hub portion 24 of the end plate 14'. An end plate 25 of the valve cylinder 16 adjacent the ports 22 is 80 also provided with ports 25' adapted to register with the ports 22 when the throttle valve is open to admit auxiliary air at high speeds. The point at which auxiliary air is allowed to enter during the opening of the 85 throttle valve can be determined by the adjustment of the valve cylinder 16 on its spindle 19 by means of set screw 26.

The heating chamber 13 above referred to in this embodiment of my invention is 90 in the form of a sphere of such diameter with respect to the diameter of the spherical part of the shell that a passageway formed between the outer wall of this chamber and the inner wall of the shell, while being of 100 comparatively large cross-sectional area, is narrow in width, so that the hydrocarbon fuel mixture is spread out in a thin stream as it flows upwardly around the outer wall of this chamber and is caused to flow in contact with the outer wall of the chamber in such manner that it is readily heated to produce the proper vaporization of the hydrocarbon. The tip of the nozzle 11 is 105 preferably brought into close proximity to the lower flaring wall of this chamber, so that the hydrocarbon will strike this heated

wall and will be dispersed uniformly over the flaring surface, which might not be the case if the gas were allowed to discharge lower down in the extension 8. The chamber 5 may be heated by any suitable means, but in the preferred form of my invention, as illustrated, I prefer to heat the chamber by hot water, since in that case the hot water from a radiator attached to the machine can 10 be used to heat the chamber. The heating chamber may be supported in any suitable manner within the inner shell, but in the present embodiment of the invention I have shown it positioned and supported within 15 the shell by pipes 27-27' which also serve to conduct the heating fluid through the chamber. These pipes pass through suitable openings in the flanges 28-28' of the upper and lower halves of the shell, and 20 these flanges are held together by suitable bolts 29, or otherwise.

While I have shown and described the best form of my invention now known to me, it is obvious that various changes in and 25 modifications of this form of the invention may be made without departing from the spirit or scope of my invention, such, for example, as a heating chamber in the form of a cylinder with a tapering lower portion, or in the form of a double cone, but the 30 present form of the invention has peculiar advantages and is more efficient than other probable forms.

Having thus described my invention, what 35 I claim as new and desire to secure by Letters Patent, is:

1. In a carbureter, the combination with two concentric hollow spheres separated by a narrow space, of means for heating the in-

ner sphere, means for delivering air and 40 fuel radially against one side of the inner sphere, and means for discharging the heated and mixed material from the opposite side of the outer sphere; whereby all the entering material is spread in a uniform 45 thin layer over the hot inner sphere and after heating and mixing is collected and delivered as hot carbureted air of homogeneous character.

2. In a carbureter, the combination with 50 an internally spherical hollow casing having on one side a relatively small radially disposed charge inlet passage and on the opposite side a corresponding outlet passage, of a concentric hollow sphere slightly 55 smaller than, and fixed within, the casing, and means for heating the interior of said sphere.

3. In a carbureter, the combination with 60 a casing provided with a spherical chamber 65 having on one side an air inlet passage and on the opposite side a charge outlet passage, of a slightly smaller hollow sphere within said chamber, hot-fluid pipes passing into 70 said chamber, communicating with the interior of said sphere and holding the latter concentric with the chamber, means within said inlet passage for delivering fuel radially against the sphere, and means for admitting a variable amount of auxiliary air to said outlet passage.

In testimony whereof, I have signed my name to this specification, in the presence of two subscribing witnesses.

JOSEPH S. BARUCH.
